UNITED STATES PATENT OFFICE.

BENJAMIN THOMPSON AND CHARLES SELDEN, OF TOLEDO, OHIO.

TELEGRAPHIC APPARATUS.

SPECIFICATION forming part of Letters Patent No. 253,957, dated February 21, 1882.

Application filed November 21, 1879.

To all whom it may concern:

Be it known that we, BENJAMIN THOMPSON and CHARLES SELDEN, of Toledo, in the county of Lucas and State of Ohio, have invented 5 certain new and useful Improvements in Telegraph Apparatus for Use upon Long Cable or Land Lines, of which the following is a specification.

Our invention relates to that class of telegraph apparatus in which signals are transmitted by the induced reversed currents from an induction-coil, and are received upon a polarized relay of any suitable construction.

In apparatus of this kind as hitherto constructed the alternate reversed impulses corresponding to the closing and opening of the transmitting-key have been produced by the closing and breaking of the primary circuit of the induction-coil. By this plan, however, the 15 impulses corresponding to the opening and closing of the key are not of the same strength, since, as is well known, the induced or secondary current produced by the breaking of the primary current and demagnetization of the core is stronger than that which is set up when the primary circuit is closed and the core 20 is magnetized.

The object of our invention is to remedy this defect and to cause the secondary reversed 30 currents corresponding to the opening and closing of the transmitting-key to be of equal strength, thus producing a uniform and certain operation of the polarized relay in response to such reversals of current.

An additional object of our invention in this connection is to increase the strength of the reversed currents.

The object of our invention is also to improve the construction of the polarized relay 40 at the receiving end of the line.

In carrying out our invention we use as a transmitter a pole-changing device instead of a circuit maker and breaker, and instead of making and breaking the current from the local battery which passes through the primary coil we reverse the polarity of the local-battery current without, however, breaking its continuity. The effect of this is to increase 45 very considerably the extent and suddenness 50 of the charge in the primary coil and the core, and consequently to increase the strength of

the induced currents. Moreover, since the change at each movement of the transmitting-key, whether up or down, is the same—viz., from a positive current of certain strength to 55 a negative current of the same strength, and vice versa—the positive current from the secondary of the induction-coil is of the same strength as the negative, and vice versa. The movements of the polarized relay at the receiving end of the line in both directions are thus made in obedience to currents of the same strength.

In Figure 1 of the drawings, F represents an ordinary pole-changing key, whose contacts M, 65 N, M', N', O, and P control, in the well-known manner, the circuit of a local battery, G, whose current flows in the one direction or the other through the primary coil I of an induction-coil, H, of any preferred construction, an earth 70 or return wire, and the contact-points of the key F, according to the position of said key. This key is a continuity-preserving key, so that the reversals of the local-battery current are accomplished without absolutely interrupting the current. The pole-changing key is 75 actuated in the ordinary manner by an electro-magnet, K², which alternately attracts and releases the key as the local-circuit key is depressed and released, so as to make and break 80 the circuit of the local battery K'. Thus when key K is closed a current of one polarity, say, flows from battery G through the primary of the induction-coil. When said key is opened the positive current from battery G is immediately succeeded by a current of the opposite 85 polarity, but of the same strength, thus producing in the secondary coil a secondary current of the same strength, but of the opposite polarity from that produced by the closing of 90 the key.

L represents the secondary coil, wound upon a portion of a core, C, of less diameter than that upon which the primary is wound. By thus constructing the core we find by actual 95 trial that the efficiency of the coil is considerably increased, and that, other conditions being the same, secondary currents of greater strength are obtained than when the core is of uniform cross-section. One end of the secondary coil is connected to earth in the usual 100 way, the other end being connected to line. In

the present instance we have shown it as connected to a differentially-wound relay interposed between the line and the induction-coil, so that the outgoing induced currents do not 5 actuate the relay at that end of the line, but do actuate the relay at the distant end. This arrangement is well known in the art, and need not be described in all its details.

R H E O represent the adjustable resistance, 10 placed in the artificial line to earth.

S represents the condenser, V the resistance, and R T the connecting-wires, of the condenser arrangement for neutralizing static discharge, patented to us by reissued Letters 15 Patent No. 8,889, July 8, 1879.

The polarized receiver consists of a short straight bar electro-magnet, B, pivoted at the point E, and provided with a contact arm or bar, D, arranged to make and break the circuit 20 of a local battery and reading-sounder in the well-known manner. Both poles of the electro-magnet are acted upon by permanent magnets *a* and *a'*, of the horseshoe or equivalent form, the poles of each magnet embracing 25 and acting upon one of the poles of the electro-magnet B. The poles of the magnets are arranged in the manner indicated by the signs + and -, so that the force tending to swing the magnet B is made up of the attractive and 30 repulsive actions existing between the four poles of two permanent magnets and the two poles of the electro-magnet. For instance, if a current of the polarity proper to cause the right-hand end of the core to exhibit polarity 35 and the left-hand end flow over the line, the electro-magnet will be caused to swing in the direction of the hands of a watch and close the local circuit, its movement being produced by the concurrent action of all four poles of the 40 permanent magnets, since in this case the repellent force due to the pole of *a*, the attractive force from its negative, and the simultaneous attractive and repulsive effects between the opposite pole of the electro-magnet and the poles 45 of the permanent magnet will all assist one another. When the line-current is reversed 50 a contrary action takes place, and the electro-magnet is turned in the opposite direction and the local circuit is broken. By this construction and arrangement the movements of the electro-magnet, even under the action of 55 weaker currents, are exceedingly energetic, and the relay itself may be readily used as a sounder. No stops other than the poles of the permanent magnet are employed, as the poles of the 60 electro-magnet may be allowed to come in contact with the permanent magnet without any difficulty from sticking, since the reversals of movement are produced by repulsive as well as attractive effects, instead of by a disturbance of the balance of attractive effects, as in some polarized relays.

Adjusting-screws for adjusting the permanent magnets with relation to the poles of the 65 electro-magnet are indicated at C C'.

Fig. 2 shows a construction of the adjusting

devices that may be employed for adjusting the permanent magnets, the poles of the permanent magnets being here shown in end view. The permanent magnet rests upon a 70 base-block, as indicated, and the adjusting-screw is mounted in standards in the ordinary way, and is seated in a groove in the upper face of the magnet, so as to prevent the latter from shifting longitudinally. Flanges upon 75 the spindle of the adjusting-screw engage with the sides of the magnet-poles, as shown, and serve to give the required lateral movement to the magnet for the purposes of adjustment.

The operation of our improved apparatus 80 will be readily understood. Normally no current flows to line. Local battery G flows through the primary of the induction-coil with a certain polarity, giving to the core of the induction-coil a magnetic polarity of a certain 85 sign. When key K is depressed the flow of the local-battery current is reversed, and the polarity existing in the core of the induction-coil not only ceases, but is instantly succeeded by a polarity of the opposite signs. The effect is 90 to cause a secondary induced current or impulse to flow to line, which is of the proper polarity to cause the electro-magnet B to turn and close the local circuit of the reading-sounder. The induced current is of but momentary duration, but the relay remains in the position assumed by reason of the attraction between 95 its soft-iron cores and the poles of the magnet with which it is in contact or near which it rests. When the transmitting-key K is opened 100 the local-battery current is reversed, assuming its normal polarity, the magnetism of the core C² is instantly changed to the opposite sign, and an induced electric current or impulse 105 of the opposite sign, but of the same strength as that produced by the closing of the key K, is sent to line, and the relay is thrown back to its first position.

We do not limit ourselves to any particular form or construction of the various elements 110 of our invention, and we wish it to be understood that other forms of induction-coil and other styles of continuity-preserving current-reversing apparatus may be used in place of that described, the object being, so far as the 115 latter element is concerned, to reverse the direction of the current charging the primary coil without interrupting its continuity. Other devices or arrangements of apparatus besides what are technically known as "pole-changing" or "reversing" keys may be used for this 120 purpose.

It is obvious that so far as concerns the combination of a polarized receiver and transmitting apparatus of the character above described any polarized receiver will answer the 125 purposes of the invention.

What we claim as our invention is—

1. The combination of a polarized receiver, an induction-coil whose secondary is connected 130 to line, and suitable means, substantially as described, for reversing the direction of the

primary current of said induction-coil without interrupting the continuity of the current, as and for the purpose set forth.

2. The combination, substantially as described, of an induction-coil whose secondary is connected to line, a primary coil in circuit with a local battery, and a continuity-preserving pole-changing key whose contact-points are in said local-battery circuit.

10 3. The combination of a swinging straight-bar electro-magnet and two permanent horse-shoe-magnets arranged each to embrace with

its poles one pole of said electro-magnet, the poles of said magnets being arranged to act as stops to the poles of the electro-magnet, and 15 adjusting devices for adjusting the poles of the permanent and electro magnets with relation to one another.
